UNITED STATES PATENT OFFICE.

ALOIS CHARVAT, OF CLAFLIN, KANSAS.

STOCK-RELEASING DEVICE.

1,308,224.

Specification of Letters Patent.

Patented July 1, 1919.

Application filed September 25, 1918. Serial No. 255,626.

To all whom it may concern:

Be it known that I, ALOIS CHARVAT, an Austrian subject, residing at Claflin, in the county of Barton and State of Kansas, have 5 invented certain new and useful Improvements in Stock-Releasing Devices, of which the following is a specification, reference being had to the accompanying drawings.

This invention relates to an improved 10 stock releasing device, and has for its primary object to provide means for quickly releasing the animal from a stall in case of fire, the releasing means being operable from the exterior of the stall and at each 15 side thereof.

It is another and more particular object 20 of my invention to provide a device for the above purpose embodying a releasing rod extending through the series of stalls adjacent the inner faces of the front walls of 25 the mangers, spaced means on the rod to coact with means attached to the halters of the animals, whereby the halters are connected to each end of said rod and operable 30 from the exterior of the barn whereby the rod may be axially shifted to release the 35 halters.

It is another one of the detail objects of 40 the invention to provide improved means for preventing the casual, shifting movement of the rod by the tugging of the animals on the halters which might effect the release of the latter.

It is also another important object of the 45 invention to provide means for insuring the free and easy operation of the locking means so that the halters will be instantly released upon the actuation thereof.

It is also a further general object of my 50 invention to provide a device for the above purpose which is simple and durable in its construction, highly efficient and serviceable in practical use, and capable of manufacture 55 at relatively small cost.

With the above and other objects in view, the invention consists in the improved construction, combination and relative arrangement 60 of the several parts as will be herein- 50 after more fully described, subsequently claimed and illustrated in the accompanying drawings in which similar reference characters designate corresponding parts throughout the several views, and wherein:—

Figure 1 is an elevation showing my im- 65

proved stock releasing means applied to a series of mangers;

Fig. 2 is a horizontal section taken on the line 2—2 of Fig. 1;

Fig. 3 is a vertical section taken on the 60 line 3—3 of Fig. 1;

Fig. 4 is a perspective view showing one of the halter locking devices in released position; and

Fig. 5 is a horizontal section through opposite ends of the shiftable rod showing the manner of connection of the operating levers thereto.

Referring in detail to the drawings, M designates a series of mangers and W the 70 front walls thereof. Each of these manger walls is centrally provided with an opening, shown at w.

To the inner face of each of the manger walls W, a casting is secured, said casting 75 including spaced side plates or flanges 5 integrally connected at one of their ends by the body plate 6, which is engaged against the inner face of the manger wall and is provided with an opening 7 which coincides 80 with the opening w. The spaced side plates 5 of this casting are formed with laterally projecting flanges 8 having openings therein to receive suitable attaching screws 9. Said casting is also formed at one side thereof and opposite the body plate 6 with a channelled extension 10, which is adapted to extend into a recess formed in the inner face of the wall W, said extension having an apertured flange to receive an attaching 90 screw 11. In the channel portion of the extension 10, an anti-friction roller 12 is rotatably mounted, the axis of said roller being vertically disposed. The side plates 5 of the casting are provided with bolt receiving 95 openings 13 in line with the roller channel. Upon the inner face of one of the side plates 5, adjacent to the attaching flange 8, an inwardly projecting leaf spring 14 is secured for a purpose which will be presently 100 stated.

15 designates an axially shiftable rod, which is freely movable through openings in the partition walls between the several mangers and also through one end wall of 105 the stable. This shiftable rod is also loosely engaged through openings 16 provided in the side plates 5 of the several castings. At one side of each of the metal castings secured to the manger wall, a yoke member 17 110

is engaged upon the rod 15. Between the arms of the yoke, a collar or sleeve 18 is engaged upon said rod and is secured thereto against shifting movement by means of a 5 cotter pin or key 19, which is disposed through registering openings in the opposite sides of the sleeve and in the rod 15. Thus, the yoke member is held against longitudinal shifting movement on the rod. To 10 the end of said yoke member, a locking pin or bolt 20 is fixed and extends in parallel relation to the rod 15. This pin or bolt is engaged in the peripheral groove of the anti-friction roller 12 and is adapted for movement through the openings 13 in the side plates 5 of the casting.

The rod 15 is provided with a short, longitudinally extending groove or channel 21 which, in one position of the rod, receives 20 the leaf spring 14. This spring acts to hold the rod against a casual, axial shifting movement when the bolt or pin 20 is disposed in its locking position through the openings 13, so that a positive longitudinal movement 25 of the rod is required to move said pin to a released position. This pin 20 is adapted to engage through a sheave yoke or holder 22 in which the peripherally grooved roller or sheave 23 is mounted. The yoke member 30 22 is connected by a link 24 to a ring 25 to which the animal halter is adapted to be attached. The roller or sheave yoke and link 24 are inserted through the opening *w* in the manger wall from the exterior thereof and the pin or bolt 20, when in locking 35 position, is disposed between the roller 23 and the medial portion of the holder or yoke 22.

Each end of the rod 15 is longitudinally 40 slotted or bifurcated, as at 26. Bearing members 27 and 28 respectively are secured in the opposite end walls of the barn or stable, and in the bearing member 27, a lever 29 is pivotally mounted intermediate of its 45 ends. To the shorter end of this lever, one end of a link 30 is pivotally connected, as at 31, said end of the lever being movable through a slot or opening 32 in the barn wall. The other end of the link 30 is en- 50 gaged in the slot or bifurcation 26 in one end of the rod 15 and is pivotally connected to said rod at the inner end of said slot by means of the pin, indicated at 33. The other end of the lever 29 terminates in a convenient finger engaging hook 34.

An operating lever 35 is also pivotally mounted at one of its ends in the other bearing member 28 and to this second lever, at 55 a point in spaced relation to its pivoted end, a link 36 is pivotally connected, as at 37, the other end of said link being engaged in the slot or bifurcation at the opposite end of the rod 15 and pivotally connected to the rod at the inner end of said slot by the pin

38. The levers 29 and 35, when the pins 20 65 are disposed in their locking positions, are seated in channels or grooves 39 and 40 respectively formed in the outer faces of the opposite end walls of the barn or stable.

In the operation of the device as above 70 described, assuming that the several animals have been locked in their stalls by means of the invention in the manner above described, in case of fire or other imminent danger, when it is necessary to release the 75 animals so that they may effect their escape from the stalls, one of the levers 29 or 35 is pulled outwardly at its curved end. Assuming that the lever 29 is thus operated, it will be at once seen that through the medium 80 of the link 30, the rod 15 will be axially shifted to the right against the holding action of the several springs 14 and the locking pins 20 will be withdrawn from the 85 openings 13 in the lefthand plates or flanges 5 of the respective metal castings until the extreme end of the pin is disposed in the opening in the other side plate. Thus, these pins are withdrawn from engagement with the sheaves or rollers 23, thereby releasing 90 the animal halters. Such release is also effected in a similar manner by operating the other of the levers 35. When this lever is pulled outwardly, the link 36, being connected to said lever intermediate of its ends, 95 will pull the rod 15 to the right and thus retract the locking pins 20. When one lever is moved to return the rod 15 to its former position, the other lever is similarly moved and both levers engaged in the grooves or 100 channels 39 and 40 of the stable or barn walls. The series of leaf springs 14 engaging in the grooves in the rod 15 securely hold said rod against any possibility of casual, shifting movement which might be occasioned by the pulling of the animals upon the halters. The rollers 12 and 23 assure the free and easy sliding movement of the locking pins 20 through the side plates 5 of the castings. In this manner, it will be 110 seen that all of the animals within the barn or stable may be instantly released by the actuation of either of the operating levers.

From the foregoing description, taken in connection with the accompanying drawings, 115 the construction, manner of operation and several advantages of my invention will be clearly and fully understood. The device consists of relatively few parts which are all of simple form and can be readily applied to the ordinary animal stall or manger without requiring material alterations therein and at relatively small expense. I have herein shown and described what I have found to be a very practical and serviceable 120 embodiment of my invention, but it is to be understood that the several elements, as herein particularly set forth, are susceptible of 125

many changes in the form, proportion and construction thereof and I, accordingly, reserve the privilege of adopting all such legitimate changes as may be fairly embodied within the spirit and scope of the invention as claimed.

I claim:—

1. In an animal releasing device, the combination with a stationary support, of a plurality of U-shaped castings fixed thereto, and having parallel spaced side plates, said side plates and the ends of the support having axially alined openings, said side plates having additional openings axially alined and offset from the first openings, a shaft provided with slotted ends and axially shiftable through the first openings of the side plates and the ends of the support, arms fixed on the shaft each extending at right angles thereto and to one side of a casting, the end parts of the arms having lateral pins movable axially through the additional openings of the side plates, when the shaft is shifted, for engagement with the devices adapted to be interposed between the side plates, the ends of the support having transverse recesses on their outer faces, a pair of levers, one pivoted in one of the recesses of one of the ends, whereby long and short arms are provided, the other pivoted in the recess of the other end, whereby only a single long arm is provided, a link pivotally connecting one of said slotted ends of the shaft and the arm of the last mentioned lever, whereby upon an outward swinging movement of said arm of the last mentioned lever, the shaft may be moved axially in one direction, and a link connecting the other slotted end and the shorter arm of the first lever, whereby upon an outward swinging movement of the first lever, the shaft may be moved axially in the same

direction as when the last mentioned lever is operated.

2. In an animal releasing device, the combination with a stationary rectangular support having end pieces in parallelism, the outer faces of said end pieces having transverse recesses, and one of the end pieces having an opening adjoining one end of one of the recesses, the other end piece having an opening adjoining the recess therein but disposed short of one end of the recess, of a shaft movable axially through the last mentioned opening and having its ends slotted, a plurality of animal releasing devices on the support and including bolts carried by the shaft, for releasing said devices when the shaft is actuated, a pair of levers, one pivoted in the recess of one end piece to provide a long arm, a link passing and operating through the last mentioned opening and connecting the long arm and one of the slotted ends of the shaft, whereby when the long arm is swung outwardly in one direction, the shaft is moved axially through the last mentioned opening, for operating the bolts of the releasing devices, the other lever being pivoted in the recess of the other end piece to provide long and short arms, a link passing through the first mentioned opening and connecting the short arm and the other slotted end of the shaft, whereby upon outward movement of the longer arm of the last lever, the shaft may be moved axially through the first opening in the same direction as when the longer arm of the first lever is operated.

In testimony whereof I hereunto affix my signature in the presence of two witnesses. 80

ALOIS CHARVAT.
